CONVEYER SYSTEM

Norval B. Griffin and Claude H. Brechner, Portsmouth, Ohio, assignors to The Selby Shoe Company, Portsmouth, Ohio, a corporation of Ohio

Application May 14, 1941, Serial No. 393,423

1 Claim. (Cl. 12—142)

This invention relates to a system of handling pieces or parts during manufacturing operations and is particularly concerned with a system of assembling the various parts of articles of the same generic type but of different detailed construction where it is desired that all of the articles be assembled at the same time by the same group of persons.

The invention will be disclosed in connection with a conveyer system for assembling the uppers of women's shoes of different types, sizes, and styles. However, its utility is not limited to this exact field and there are doubtless other manufacturing problems in which the invention will be of equal utility.

The invention is not concerned with the details of the mechanical structures involved in its practice but rather in the system as the same will be hereinafter described. However, some disclosure will be made of mechanical expedients useful in the practice of the invention in order to better explain the operation of the system.

In the fitting room of a large women's shoe factory, there is the continuous problem of assembling simultaneously a large number of different types and styles of shoes. Since shoe styles change seasonally, and since most manufacturers present a large number of new styles during each season, but, at the same time, retain many of the old, there is always a continuing demand for a large number of styles. It is practically impossible to build up stock in many styles because, until the shoes are actually ordered, it is impossible to foretell whether the style will have commercial acceptance. Surplus stock in seasonal models must be avoided at all costs.

Practically all of the fitting or assembling of uppers is done in a series of individual operations by hand labor or unit machine labor; that is, by the use of a machine such as a sewing machine for a single operation. In the case of a large manufacturer, it is not possible to keep one group of workers continuously busy in the assembly of one particular style of shoe as there are usually too many styles for this to be a practical procedure. Resultantly, it is common manufacturing practice for a single group of workers to work on a number of different styles at the same time. As this method operates, practically, each worker has a particular set task which he or she performs continuously. For example, this may be a cementing operation, formation of an eyelet, a marking or inking operation, or some other conventional step in the assembly of a shoe upper. As each worker finishes a certain number of pieces, he passes them on to the person

5 who is to perform the next operation. Since the group is working on a number of different styles, and since the course of assembly of various styles may be, and usually is, entirely different, one worker does not always pass his completed pieces to the same succeeding worker. In the assembly of some styles, the worker may pass his pieces to a person sitting next to him, while in the assembly of other styles, it may be necessary for him to pass his pieces to someone all the way across the fitting room.

10 As a result, it has been a difficult problem to arrange the workers in a fitting room so that there will be a minimum of time spent in passing the pieces completed by one worker to the next worker. As an illustration of the extent of this problem, it has been estimated that ten percent of all of the workers in a fitting room are at all times engaged in standing on their feet and passing completed pieces from one to the other rather than in sitting at their desks performing their particular operation.

15 The need for some sort of conveyer system to meet a condition of this sort is obvious, but the problem of providing one has not been easy of solution. The major difficulty occurs because for practical reasons it is impossible to synchronize the course of operations so that the completed pieces will go in one direction only and so that they can be conveyed by a conventional conveyer belt. To illustrate this, assuming a group 20 of 38 or more workers of the type which will be hereinafter more fully described in connection with the drawings, and assuming each worker represents a particular numbered operation, the course of assembly of one particular upper is as 25 follows: 2, 3, 4, 5, 13, 18, 8, 12, 19, 17, 21, 22, 26, 27, 24, 28, 29, 30, 36, 33, 34, 35, 29, 30, 31, 37, 38, while the course of another representative upper 30 is as follows: 1, 3, 4, 6, 19, 17, 10, 8, 12, 28, 11, 8, 12, 13, 18, 8, 19, 17, 23, 24, 25, 26, 28, 31, 36, 37, 38.

35 It will be noted from this that in order to provide an effective conveyer system, it is necessary to have means for transporting the finished pieces in either direction. For example, in the first illustration, it is necessary for operator 13 to have at his command means for transporting his finished pieces to operator 18, and it is necessary for operator 18 to have at his command means for transporting his finished pieces back to operator 8.

40 With the solution of this and other problems relating to conveyer systems of this type in mind, one object of the present invention has been to 45 provide a conveyer system in which the completed pieces may be transported mechanically to the

operator next required to work on them regardless of the positioning of this operator with reference to the first operator.

Another object of the invention has been to provide a system of conveying pieces in which all of the available working space adjacent the conveying instrumentality may be utilized without creating any problem of ingress or egress of the workers.

Another object has been to provide a conveyer system particularly useful in a manufacturing operation where it is necessary for a group of people to work simultaneously on a large number of articles of the same general nature but of different detailed construction.

Another object has been to provide a conveyer system in which the articles may be placed on and removed from the conveyer with a minimum of effort and inconvenience.

Other and further objects and advantages will be apparent from the consideration of a further and more detailed description of the invention when considered in conjunction with the drawings in which:

Figure 1 is a diagrammatic plan view of a typical conveyer system representative of the invention.

Figure 2 is a perspective view somewhat diagrammatic of the general arrangement of the conveyer belts.

In Figure 1 the preparation table is indicated at *a*, the upper belt at *b*, the lower belt at *c* and the belt turns at *d*. Each of the operators is assigned a number in sequence although it will be noted that there are various duplications of the numbers where the same operation is performed by more than one person.

Beginning the operation of the system, assemblies are prepared of all of the pieces necessary for the construction of a particular upper. This is done at the preparation table *a* by one or more workers skilled in this particular duty. At this table also, a slip or chart is prepared itemizing the sequence of operations in the formation of the particular upper. This slip may be included in a box or other container along with the pieces. A typical slip is herewith reproduced, the sequence of operations being the same as that referred to in the previous example first given.

No.	Operation	No.	Operation
2	Mach Mark (vp for qr & tack, 4M-380 2 pcs at a time) (vp for tip, 4M-381 2 pcs at a time)	26	Eyelet Stay & Tack Mark (drill stay) (tack mark)
3	Ink (tip-line of tip)	27	Cement Tong to Ling
4	Iron (Blu. points)	24	Lay Linings
5	Brace (Tufta to qr) (cut-to-fit)	28	Top Stch (tong, trim all around) (qr, wad at bk. trim at all around) (trim after top stch)
13	Close (vp, 1 row, matched seams) (backseam, 1 row)	29	Cement for Die out (qr) "X" Dept—Die out or cut out, Model "K", 4F-525
18	Tape seam (backseam)	30	Eyelet Sort (vps) (grs)
8	Fit Trim (beveled vp seam at lower end; cement tip to vp)	34	Vamp (1 row to within $\frac{1}{4}$ of nose, holding ling back)
12	Flat Fey Stch (tip to vp & stch 2nd row on tip)	35	Side Seam
19	Cement (vp, hand) (qr, mach. or hand)	29	Cement for Die out (inc. box toe)
17	Fold (vp, Glass) (qr, Glass)	30	"X" Dept—Die out vp cutout, Model "K" 4F-526
21	Fr Bnd	31	Post Stch (Finish vamp & tack & lm on vp & qr & cutouts)
22	Fr Fold (inc. nicking)	37	Ensign Lace
		38	Final Sort (inc. equalize)

The box containing the slip is first delivered manually to the operator first required to work on this particular upper, which in this case is operator 2, who performs a machine marking operation.

When operator 2 has performed his particular operation it is necessary that the box be passed to operator 3 for an inking operation. Since operator 3 is farther along to the right than operator 2, the box is then placed on the upper belt *b* which moves continuously in that direction. Upon reaching operator 3 it is removed, the inking operation is performed and the box is then replaced on the belt to pass in sequence to operators 4, 5, 13 and 18. After operator 18 has finished his tape seaming operation the slip or chart calls for a return of the box to operator 8. Since operator 8 is to the left of operator 18 the box is placed on the lower belt *c* which moves in that direction. In this way the box passes through the complete sequence of the indicated operations until it finally reaches desk 38 for the final sort and hand trim. From here it is placed on a truck and removed as a finished article.

The belts utilized are conventional conveyer belts except that a particular U-shaped arrangement is preferably employed which enables the operators to position themselves at every available point without causing any problem of ingress or egress to their work benches. As indicated by the arrows, the upper belt, which is in effect three separate belts, moves continuously from position 1 to position 37. The lower belt which is similarly constructed moves continuously from position 37 to position 1. As best indicated in Figure 2, the two sections of each belt are joined together by a cross-over belt *e* which coordinates the operation of the different sections of the upper and lower belts. In the operation of the cross-over belt, the boxes proceed

along one section of one of the belts, such as for example the right hand section of the upper belt, until they contact the snubbers or belt turns *d*. The continuous movement of the upper belt pushes the box around this snubber until it is finally taken up by the cross-over belt. The same operation is performed at the second snubber and in this way the U-turn is completed. The belts may have stops at either end to prevent the boxes destined for a terminal end from being carried off onto the floor.

In the operation of the system, it has been found highly advantageous to utilize a signal system of different colored index tabs or flags. Each operator may have a box containing a complete set of these flags numbered with the numbers of the operator to whom that operator delivers his pieces. When the first operator finishes his operation he may then select an index flag bearing the number of the operator expected to perform the next operation and place it conspicuously on the edge of the box. This flag will of course bear the distinctive color of the particular operator for whom the box is destined. It has been found that the operators maintain a sort of subconscious lookout for boxes bearing flags of the color assigned to them and that in actual operation there are very few occasions when the box passes the operator for whom it is intended. It is not essential that there be a different color for each operator and a series of six or seven colors used in rotation works satisfactorily as the flags are additionally identified by number.

The operators may utilize work benches of similar construction although in some instances par-

ticular equipment will be required for certain operations. The belts should be positioned at the most convenient height consistent with the benches used and it has been found that it is quite advantageous to have the lower belt about the knee height and the upper belt about the eye height of a seated operator.

In the operation of the system it is possible for a group of the size indicated in Figure 1 to work on as many as sixty different styles of uppers simultaneously without the occasion arising for an operator to leave his work bench to pass the work to another operator. Since in these sixty styles each style will follow a different sequence of steps, the result of the use of the system is to greatly facilitate the transfer of the pieces and to greatly improve the general efficiency of the assembly operation.

Having fully described our invention we desire to be limited only by the ensuing claim.

We claim:

5 The process of manufacturing shoe uppers, comprising the steps of; preparing and collecting the parts making up the uppers; delivering the assembled parts to the first operator indicated on a work sheet initially assembled with the collected parts; indicating by means applied 10 to the collected parts the next station to which they are to be despatched; and finally shuttling the collected parts back and forth between stations, as indicated on the work sheet, by means of conveyer belts travelling in a U path and including reverse runs for delivery of the parts in 15 either direction.
